ELECTRICAL HEATING APPLIANCE

Arthur J. Kercher, Berkeley, Calif.

Application August 18, 1930. Serial No. 475,875

5 Claims. (Cl. 200—138)

This invention relates generally to appliances for electrically heating various mediums, and is particularly adapted for use in conjunction with electrical water heaters. It also relates to the construction of thermostat or temperature responsive switches.

It is an object of the invention to devise a novel appliance of the above character which will have provision for the automatic control of the current supply in accordance with temperature changes. The appliance as will be presently described is characterized by simplicity of structural features, by ease of manufacture and assembly, and by the fact that it can be readily 10 adjusted and serviced when in use.

It is a further object of the invention to devise a thermostat switch which will be relatively sensitive to temperature changes and in which the electrical contacts will be operated in a 15 positive manner.

Further objects of the invention will appear from the following description in which the preferred embodiment of the invention has been set forth in detail in conjunction with the accompanying drawing. It is to be understood that the appended claims are to be accorded a 20 range of equivalents consistent with the state of the prior art.

Referring to the drawing:

Figure 1 is a side elevational view in cross section, illustrating an appliance incorporating the present invention.

Figure 2 is a cross sectional view taken along the line 2—2 of Fig. 1.

Figure 3 is a cross sectional detail taken along the line 3—3 of Fig. 1.

Figure 4 is an end view of the appliance shown in Figs. 1 and 2, with the cover of the head-like 40 mounting removed.

Figure 5 is a diagrammatic view illustrating operation of the thermostat switch.

The appliance as illustrated in the drawing consists of an electrical heating element 10 which is preferably elongated in form, and which has its one end secured to a head-like casing or mounting 11. While various sizes of electrical heating elements can be employed, the particular construction shown is similar to that illustrated in Figs. 2 and 3 of Kercher and Hicks Patent No. 1,671,592 granted May 29th, 1928. It can be described briefly as comprising a sealed tubular sheath 12 made of suitable metal, such as copper, within which a coil 55 resistance conductor 13 is disposed. To provide

suitable insulation a plurality of refractory insulating tubes 14 are strung upon conductor 13. The terminal wires 15 for conductor 13 extend through one end of tubular sheath 12, while the other end of the sheath is sealed. 60 Mounting 11 can be conveniently made of a suitable metal casting, and is provided with a portion 16 of reduced diameter adapted to be secured to the wall 17 of a water tank or other liquid container. In practice it is convenient 65 to provide portion 17 with a pipe thread 18 which can be screwed into the tank or container wall 17 to form a liquid tight connection. The inner end of portion 16 is welded or provided with an equivalent liquid tight joint with the 70 adjacent portion of sheath 12.

The enlarged outer portion of mounting 11 is head like in form, and it is preferably hollow to accommodate the thermostat switch to be presently described, and to accommodate the 75 conductors for making an electrical connection with heating element 10. Thus one convenient form for the interior of mounting 11 is to provide that portion of the mounting within portion 16 with a cylindrical bore 21, and the 80 outer enlarged portion of mounting 11 with an enlarged cavity 22. Ordinarily the interior mounting 11 is closed by a suitable removable cover plate 26.

The thermostat switch and its associated parts 85 preferably consist of a metal tube 27, adapted to be telescopically disposed within the cylindrical bore 21. A metal plate 28 is secured to the outer end of tube 27, and this plate serves to carry certain terminal connectors and other 90 parts to be presently described.

The electrical contacts for controlling the supply of current to the heating element 10 consist in this instance of a movable contact 29, carried upon one end of the movable arm 95 31, and a relatively stationary contact 32. Stationary contact 32 is carried by a member 33 extending outwardly from plate 28, and which is mounted upon L shaped member 34. Member 32 is bent to form an extending portion 100 which is provided with a suitable connection terminal 36. One portion of a conductor bar 37 is interposed between plate 28 and laterally bent portion 34, and is likewise provided with a terminal connector 39. A bolt 41 passes through plate 28, bar 37, and member 34, to 105 securely clamp these parts together. Insulating strips or washers serve to insulate portion 34 from conductor bar 37, and to also electrically insulate these parts with respect to metallic 110

plate 28. Other terminal connectors 43 are mounted upon plate 28 and are electrically insulated from the same. The inner end of bolt 41 serves as a stop to limit opening movement of contact 29.

For effecting movement of contact 29 responsive to temperature changes, I have illustrated means consisting of a pair of bimetallic strips 46 and 47 which are adapted to flex in response to temperature changes. Strips of this character are well known in the art and are formed of laminæ of different metals, brazed, welded or otherwise secured together, and having different temperature coefficients of expansion.

In order to mount strips 46 and 47, the inner end of tube 27 is provided with a plug 48 made of suitable material having relatively good heat conductivity, such as metal, and which is slotted 20 to receive the inner ends of strips 46 and 47.

The strips are locked within plug 48 by means of rivet pin 49, which also serves to lock the plug to tube 27. Apertures 51 are formed in plug 48, through which the terminals 16 from the resistance conductor 13 can extend. Tube 27 is also shown provided with slots 52, communicating with opposed channels or grooves 53 in mounting 11, whereby the terminal conductors 16 can be extended to the interior of tube 27, through channels 53, into the enlarged cavity 22.

Bimetallic strips 46 and 47 are extended to the outer side of plate 28, where they cooperate in a novel manner to conjointly effect operation of arm 31. Thus the outer end of bimetallic strip 46 is provided with a laterally bent portion 56 and interposed between this portion and the opposed outer end of strip 47 there is a pivoted toggle bridge 57.

The preferred construction of toggle bridge 57 can be made clear by reference to Fig. 1. In this view it will be noted that the end of arm 31 remote from contact 29 is provided with a portion 58 of enlarged width. Portion 58 is provided with a plurality of aligned apertures 59 within which studs 61 are disposed. The studs are preferably of metal and are insulated from metallic portion 58 by suitable means such as the apertured insulating strips 62. Aligned pivot pins 63 project from studs 61, and the plane of the points of these pins is substantially at right angle to the arm 31 and substantially at right angle to the directions of flexing of bimetallic strips 46 and 47. Mounted upon the outer end of bimetallic strip 47 there is a portion 64 formed with a groove 66, within which the pivot pins 63 on one side of bridge 57 engage. The pivot pin 63 upon the other side of bridge 57 engages in a recess 67 provided in the head 68 of a plunger 69. Plunger 69 is preferably adjustably mounted upon laterally bent portion 56, for a purpose which is to be presently explained. Thus it is shown slidably disposed within a sleeve 71, and this sleeve in turn is disposed within a slot 72 formed in laterally bent portion 56. An eccentric or cam 73 is formed upon the inner end of sleeve 71, while the outer end of the sleeve is formed with a finger engaging portion 74. A compression spring 76 serves to normally bias plunger 69 inwardly upon the corresponding pivot pin 63. An abutment member 77 is secured to laterally bent portion 56, and serves to retain sleeve 71 within slot 72, and also serves to engage the surface of eccentric 73. It is evident that by maintaining the surface of eccentric 73 in contact with abutment 77, rotation of sleeve 71

through 180° will serve to continuously vary the position of plunger 69 with respect to bimetallic strip 46.

In installing the appliance described above it is evident that contacts 29 and 32 are connected in series with the electrical heating element 10 and in series with the source of current supply. Thus assuming a single phase source of current supply, one of the current supply lines can be connected to one of the terminal connectors 43, and the other to terminal connector 36. One of the terminal conductors 16 from the heating element 10 can be connected to terminal connector 39, and the other to the other terminal connector 43. Terminal connector 39 is connected to movable contact 29 by flexible conductor 79. Thus, since terminal connectors 43 are directly electrically connected together, the contacts 29 and 32 are connected in series with the heating element 10.

To describe operation of the appliance it will be presumed that it is mounted upon a wall 17 of a water tank, to form an electrical water supply heater. If the water adjacent element 10 is relatively cool contacts 29 and 32 are closed and current is supplied to the heating element. As the water surrounding the element 10 becomes heated, the temperature of portion 16 of the mounting 11 is also heated and heat is conducted to bimetallic strips 46 and 47 through tube 27 and through the metal plug 48. Strips 46 and 47 are so disposed that they tend to flex in opposite directions responsive to like changes in temperature, and therefore when they are heated to a certain predetermined degree their flexing imposes a turning couple upon toggle bridge 57, serving to rotate this bridge to move arm 31 in a direction to open contact 29. Assuming now that the water in contact with element 10 becomes cool, either by replacement of the hot water with cooler water, or by dissipation of heat, bimetallic strips 46 and 47 are likewise cooled, and they then serve to impose a turning couple upon bridge 57 in the opposite direction to effect closing of contact 29.

It is characteristic of toggle bridge 57 that its movements are relatively rapid, thus effecting rapid and positive opening and closing movements of contact 29. This characteristic is due to the fact that it functions as a toggle, due to the bias which is imposed upon it by virtue of compression spring 76. This toggle effect can be better explained by reference to Fig. 5. In this view toggle bridge 57 has been indicated diagrammatically, and the bias imposed upon it by virtue of compression spring 76 has been represented by the force components 1 and 2. Assuming a closed position of contact 29, corresponding to the solid lines in Fig. 5, it will be noted that force components 1 and 2 are slightly out of line with the result that in such position of bridge 57, the bridge is subjected to an appreciable turning couple tending to hold the contacts closed. Assuming now that bimetallic strips 46 and 47 are heated to a sufficient temperature to effect opening of contact 29, the force components imposed upon bridge 57 by flexing of strips 46 and 47 can be represented by components 3 and 4. These components 3 and 4 must first overcome the turning couple created by components 1 and 2 after which bridge 57 moves past dead center position to the position indicated in dotted lines in Fig. 5 corresponding to open position of contact 29. In

this second position shown in dotted lines in Fig. 5, the bridge is likewise under an appreciable turning couple by virtue of components 1 and 2, so that this couple must likewise be overcome when strips 46 and 47 are cooled to flex in an opposite direction. Thus for each movement of bridge 57 to effect opening or closing movement of contact 29, the bridge moves past a dead center position. This mode of operation results in rapid and positive opening and closing of the contacts.

In addition to the advantages of my invention which have been pointed out above, the positive action of the contacts is not effected at a sacrifice of sensitivity. This characteristic is by virtue of the fact that bimetallic strips 46 and 47 act additively in opposite directions upon the toggle bridge 57. Thus the strips need not be of excessive length, and they may be relatively rugged in construction to make possible reliable operation over long periods without frequent servicing.

It is apparent that adjustments of the angular setting of sleeve 71 makes it possible to effect opening and closing of the circuit at different points along a substantial temperature range. Thus when the device is incorporated in an electrical hot water supply heater, sleeve 71 can be set at such an angular position as to maintain the source of supply of hot water at a predetermined temperature.

I claim:

1. A thermostat control device comprising a thermoresponsive switch, said switch comprising a pair of bimetallic strips, one end of each of said strips being relatively fixed and the other ends being free and adapted to move in opposite directions in response to a change in temperature, a toggle bridge member interconnecting the free ends of said bimetallic strips and adapted to be rocked in accordance with the relative movement between the strips, a contact carrying arm mounted on said toggle bridge, and means for varying the inclination of said bridge relative to the ends of the bimetallic strips on which it is mounted, thereby altering the operation of said switch.

2. A thermostat control device comprising a thermoresponsive switch, said switch comprising a pair of bimetallic strips, one end of each of

said strips being relatively fixed and the other ends being free and adapted to move in opposite directions in response to a change in temperature, a toggle bridge member interconnecting the free ends of said bimetallic strips and adapted to be rocked in accordance with the relative movement between the strips, a contact carrying arm mounted on said toggle bridge, and eccentric means for moving the point of support of one end of said toggle bridge to effect a corresponding variation in the operation of said switch.

3. In a device of the character described, a pair of bimetallic strips adapted to flex in response to temperature changes, a mounting to which corresponding ends of said strips are fixed with the free ends of said strips in spaced opposed relationship, a pivoted toggle bridge, portions secured to the free ends of said strips having pivotal connection with said bridge and means for laterally shifting the position of one of said portions relative to its corresponding strip.

4. A thermostatic control device comprising a fixed support, a pair of bimetallic strips having adjacent ends secured to said support, said strips extending in the same general direction, a laterally extending portion secured to the free end of one of said strips, a switch arm, and a toggle bridge member secured to one end of the switch arm and interconnecting said laterally extending portion and the free end of the other bimetallic strip, said strips being adapted to flex toward or away from each other for like changes in temperature.

5. A thermostatic control device comprising a tubular member, a pair of bimetallic strips extending longitudinally within said tubular member, means for securing adjacent ends of said strips to one end of said tubular member, a laterally extending portion secured to the free end of one of said strips, a switch arm, and a toggle bridge member secured to one end of the switch arm and interconnecting said laterally extending portion and the free end of the other strip, said strips being adapted to flex toward or away from each other for like changes in temperature to effect rocking of said toggle bridge member.
